UNITED STATES PATENT OFFICE.

CHARLES HOWARD SMITH, OF SHORT HILLS, NEW JERSEY, ASSIGNOR TO INTERNATIONAL COAL PRODUCTS CORPORATION, OF RICHMOND, VIRGINIA, A CORPORATION OF VIRGINIA.

FURNACE RETORT.

1,414,159.

Specification of Letters Patent. Patented Apr. 25, 1922.

Application filed November 22, 1919. Serial No. 340,034.

To all whom it may concern:

Be it known that I, CHARLES HOWARD SMITH, a citizen of the United States, and a resident of Short Hills, in the county of 5 Essex and State of New Jersey, have made certain new and useful Improvements in Furnace Retorts, of which the following is a specification.

The invention relates to furnace retorts 10 of the type, for example, shown in my copending applications for United States Letters Patent Serial Number 217,764, filed February 18, 1918, or Serial Number 233,422, filed May 9, 1918. In each of said applications there is shown and described a furnace retort construction wherein a portion of the shell of the retort is defined by a longitudinally extending tubular inner wall which in cross-section is of inverted heart- 20 shape.

According to the construction shown in each of said copending applications coal is fed into the retort at one end, the charging end, by means constructed so as to prevent 25 the entrance of air into or the escape of gas from the interior of the retort while the coal is being fed into the retort. The coal within the retort is subjected to a carbonizing or distilling operation while being 30 mixed or agitated, and also conveyed along the retort from the charging end to the other or discharging end, by the mixing and conveying means that embodies a pair of parallel shafts each carrying paddles thereupon 35 and arranged so that the paddles on one shaft cooperate with and overlap the paddles on the companion shaft, the paddles being shaped so that they effect the conveying as well as the mixing or agitating.

40 The coal, when it reaches the discharge end of the retort, is a partially carbonized residue and this partially carbonized residue is discharged from the interior of the retort through a suitable discharge mechanism 45 constructed so as to permit or effect the discharge without allowing the entrance of any substantial amount of air to the interior of the retort and without allowing the escape of any substantial amount of gas from the 50 interior of the retort.

Also, according to the construction in each said copending application, the vapors and gases evolved during the carbonizing or dis-

tilling operation are withdrawn through suitable piping leading from the interior of 55 the retort.

The heat for the retort shown and described in each of the aforesaid copending applications is provided in combustion chambers arranged at and on the exterior of 60 the tubular inner wall construction or retort shell, particularly at the lower and side portions thereof.

In the partial carbonizing or distilling of coal, according to the method described in 65 each aforesaid copending application, it has been found by experience that a substantial layer of carbon is deposited at and along the interior bottom and side portions of the retort shell, particularly opposite the hot zones 70 of the combustion chambers on the exterior of the retort shell, and this carbon deposit renders advisable the employment of means for lessening or eliminating the objectionable features thereof. Said carbon deposit 75 is hard enough to effect a considerable wear on the outer ends or tips of the paddle blades which blades have heretofore been made of cast metal, usually of cast steel.

According to one aspect of the present invention it is proposed to supply the tip portion or outer end of each of the paddle blades with an anti-wearing, cutting, or scraping member of hard material, substantially harder than the paddle blade, and to 80 secure this member to the paddle blade in a suitable manner, as by riveting, by bolting or even by welding. The material which may be used for this purpose is a self-hardening steel—a steel that is hard even at 85 red heats.

Each paddle in the aforesaid copending applications is shown and described as comprising a rolled metal shank member and a blade member cast about one end of the shank member in a manner whereby said blade and shank members are rigidly secured. In the construction shown in each copending application the blade is symmetrically arranged with respect to the 95 shank member, the shank member being located at the inner end of the blade member and aligned with the central tip portion of the paddle. Also, in the paddle construction just referred to the inner end of the 100 blade member is provided with a resistance 105

shoulder or pad that engages the shaft and the shoulder or pad is symmetrical with respect to the shank member.

According to another aspect of the present invention the construction is such that the forward edge of the tip portion of the blade is in substantial alinement with the shank member and the resistance shoulder or pad, with which the blade member is provided, is unsymmetrical with respect to the shank member and extends rearwardly in the path of travel a greater distance than it extends forwardly. In fact the resistance shoulder or pad, according to the present invention, 15 extends rearwardly a greater distance than is the case in the corresponding construction of the copending applications. This resistance shoulder or pad serves to receive the paddle thrust and to transmit it to the shaft 20 in an advantageous manner and with a minimum strain on the paddle, particularly upon the shank member by which the paddle is clamped or secured to the shaft. By constructing each paddle so that the shank and 25 the forward edge of the blade are in alinement and so that the rearward extension of the shoulder or pad is relatively large there is enabled to be realized a stronger paddle construction than is the case where the shank 30 and blade members are symmetrically arranged.

As showing specifically how the invention may be realized reference is made to the accompanying drawings forming a part of 35 this specification, in which drawings,

Figure 1 shows in cross-section a furnace retort similar to that shown in my copending application Serial No. 233,422. According to the construction shown in this figure 40 the outer or tip end of each paddle is illustrated as provided with a tip member of self-hardening steel riveted to the blade member.

Figure 2 is an enlarged face view of the 45 tip portion of one of the paddles shown in Figure 1.

Figure 3 is a sectional view of the tip portion of the paddle shown in Figure 2.

Figure 4 is a cross-sectional view of a furnace retort similar to that shown in my copending application Serial No. 233,422, the 50 forward edge of the tip portion of each paddle blade of this figure being in substantial alinement with the shank member of the paddle. This figure also shows a resistance shoulder or pad the major portion of which 55 extends rearwardly.

Figure 5 shows in plan a section of one of the shafts with the paddle thereupon, four 60 paddles, each in a different position, being illustrated.

Figure 6 is a view looking lengthwise of the axis of the paddle carrying shaft and toward the operative face of the paddle 65 shown in Figures 4 and 5. From Figure 6,

especially when taken in conjunction with Figure 7, it is readily seen how the shank member alines with the forward edge of the tip portion of the blade member.

Figure 7 is a view of the paddle looking 70 at the shank member and beyond it toward the outer end portion or top of the paddle.

Figure 8 is a view taken as on the plane indicated by the line 8-8 of Figure 7 looking 75 in the direction of the arrows.

Figure 9 is a sectional view taken as on the plane indicated by the line 9-9 of Figure 6 looking in the direction of the arrows.

Referring now to the drawings in detail, 80 1 designates the retort, which is frequently referred to as a furnace retort because the shell of the retort is exteriorly heated by products of combustion in the combustion chamber of a furnace. The shell of the retort has a portion designated by 2 and is frequently referred to as the tubular inner wall construction or retort shell. This shell is exteriorly heated by products of combustion that are within combustion chambers or spaces 3 provided in the furnace portion of the furnace 85 retort.

In Figure 1 and also in Figure 4 there is indicated a pair of parallel shafts 4 each carrying radiating paddles thereupon the free ends or tips of which paddles are brought adjacent to the interior of the bottom and side portions of the retort shell as the shafts rotate. The paddles are arranged so that the paddles on one shaft cooperate with and overlap the paddles on the companion shaft 90 as the shafts rotate. The paddles in Figure 1 are indicated by the numeral 5 and those in Figure 4 by the numeral 8. Only a cross-sectional view of the furnace retort is illustrated in this case as details of construction 95 are fully set forth in each of the aforesaid copending applications, but it will be here pointed out that the general features of the retort, shaft and mountings therein may be the same as shown and described in my copending application Serial No. 233,422 and therefore further description at this time is deemed unnecessary.

The paddles shown in Figure 1 are of the same construction as shown in either of the aforesaid applications, with the exception that there is provided at the outer end or tip of each paddle blade a hard steel tip member 6 which is secured in place, as by rivets 7, in the manner fully indicated in Figures 115 2 and 3. These hard metal tip members 6 are furthermore preferably located at and preferably extend the full width across the forward side of the paddles in a manner whereby they will act as scrapers or planer tools to cut away or remove some of the carbon deposit or to delimit the carbon deposit as the shafts rotate in the direction indicated by the arrows, it being borne in mind, as previously indicated, that the car- 120 125 130

bon tends to collect or deposit along the interior bottom and side portions of the retort. The coal within the retort is subjected to a temperature, for example, approximately 5 850° and in some instances still higher with the result that the paddle blades at times become dull red. The tip member at the end of each paddle blade must be of a character that it will remain hard, even at the 10 temperatures to which the paddle blade is liable to be subjected. This tip member is therefore preferably of a suitable high-speed tool-steel, such as is obtainable at the present time. Tool-steel of the type in question is 15 frequently referred to as an air-hardening steel or as self-hardening steel, since even after heating to a cherry or red heat it both has and maintains the strength and hardness which enables it to perform its cutting function without losing its cutting properties. 20

This tip member may be referred to as an anti-wearing member, being hard enough and tough enough to withstand to a substantial degree the wear incident to the passing 25 along and scraping of the carbon which deposits on the interior of the retort shell. The path of the tip member of the paddle blade delimits the extremity to which the carbon deposit can form. Any carbon deposited or tending to be deposited so that the deposit extends within the path (or paths) of travel of the tip members, or in other words so that the carbon deposit extends beyond the line which defines the outermost 30 limits of the path is cut away or removed from the rest of the layer of deposit by the tip members functioning in the manner described. Each paddle 5 shown in Figures 35 4 to 9 inclusive has a tip member 9 at the outer end of the blade member which tip member is located in a recessed portion 10 and is held in place by rivets 11. These tip members are of self-hardening steel and are similar to and function in the same manner 40 as the tip members heretofore described. Each of the blade members shown in Figures 4 to 9 comprises a shank member 12 that is of wrought metal—rolled steel—in the form of a bolt or rod threaded at each end, and 45 the blade member is made of steel cast about one end of the shank member. The construction is such that the shank and blade members are firmly and rigidly secured together in a manner whereby a permanent connection is provided between them. The inner 50 end of the blade member, to wit, the shank end thereof, is provided with a resistance shoulder or pad 13. When the paddle is in the position in which the forward edge of the 55 tip end of the blade is practically directly below the axis of the shaft which carries the paddle then this resistance shoulder or pad is in plan practically a rectangle, as will be manifest from an inspection of the blade 60 marked "B" in Figure 5, or from an inspec-

tion of Figure 7. From each of these figures it will also be observed that the forward or operating face of the blade portion of the paddle slopes relatively to the axis of the shaft. From Figures 4, 5 and 6 it will be 70 seen that the forward tip edge 14 of the paddle is in substantial alignment with the shank member 12 that passes through the shaft and serves as means whereby the paddle is clamped or secured in place, and from 75 the same figures, when taken in conjunction with Figure 7, it will be noted that the major portion of the resistance shoulder or pad extends rearwardly from the shank member. In other words, Figure 7 clearly shows that 80 this shoulder or pad is unsymmetrically arranged with respect to the shank member, the major portion of the shoulder or pad being on the rear side of the shank member. It will also be seen that this shoulder or pad 85 extends rearwardly from the shank member past a plane which includes the axis of the shaft and that passes through the rear tip edge 15 of the paddle.

By constructing the paddles in the manner 90 shown in Figures 4 to 9 the parts are in an arrangement whereby the forces are advantageously taken care of. In other words, due to there being a relatively long distance between the center line of the shank member 95 and the extreme portion 16 of the shoulder or pad the compression strains at portion 16 and the tension strains on the shank member 12 are rendered small as compared with a construction where the same size of resistance 100 pad is employed but in which the resistance pad is symmetrical with respect to the shank member.

The improvements herein set forth are not limited to the precise construction and arrangement shown and described for they may be embodied in various forms and modifications without departing from the spirit and scope of the invention.

What I claim is—

1. A furnace retort for carbonizing coal therein within which retort there is a shaft carrying paddles each provided with a tip member of hard metal riveted to the blade portion of each paddle.

2. A furnace retort the shell of which retort comprises a longitudinally extending inner wall construction within which there is a longitudinally extending shaft with rotating paddles secured to and carried by the 120 shaft, each of which paddles comprises a blade with a tip member of self-hardening steel at the outer end of the blade.

3. A furnace retort having a longitudinally extending inner wall construction providing a portion of the retort shell, and having a pair of longitudinally extending shafts within said inner wall or retort shell, which shafts carry paddles and are arranged so that the paddles on one shaft overlap the 125 13

paddles on the other shaft, each of which paddles has a blade with a tip member secured to the outer end of the blade by means such as rivets.

- 5 4. A carbonizing furnace of the class described having a longitudinally extending wall or retort shell with parallel longitudinally extending shafts therein, which shafts carry paddles and are arranged so that the 70
10 paddles on one shaft cooperate with and overlap the paddles on the adjacent shaft, each of which paddles comprises a wrought metal shank member in the form of a bolt or rod by means of which the paddle is secured 75
15 in place on its shaft and a blade member cast upon the shank member, the construction being such that each blade member has a resistance shoulder or pad that engages its corresponding shaft, the blade member also having an operating face that makes a substantial 80
20 slope with the axis of the shaft, the blade member being characterized by having a major portion of the shoulder or pad extending rearwardly from the shank member 85
25 along the path of rotation and by having the forward tip edge of said blade and the shank member in substantial alinement.
30 5. A carbonizing retort of the class described having a longitudinally extending wall or retort shell with a pair of longitudinally extending shafts which carry radiating paddles and which paddles are arranged so that the paddles on one shaft cooperate with and overlap the paddles on the 90
35 companion shaft, the paddles being constructed so that each comprises a blade member and a wrought metal shank member in the form of a bolt or rod, which bolt or rod passes through the shaft and serves to secure the 95
40 paddle in place on the shaft, each blade member having a resistance shoulder or pad with a portion that extends rearwardly from the shank member, the shaft and paddle construction being characterized by having the forward tip edge of the paddle substantially 100
45 in alinement with the shank.
50 6. A furnace retort having a longitudinally extending inner wall or retort shell with a longitudinally extending shaft therein, which shaft carries radiating paddles the tips of which are brought adjacent to the interior of the bottom and side portions of the shell as the shafts rotate each of which 105
55 paddles comprises a shank member in the form of a bolt or rod that enters the shaft and serves as means whereby the paddle is secured to the shaft, and a blade member firmly secured to the shank member each blade member having a rearwardly extending 110
60 resistance shoulder or pad in engagement with the shaft, the blade member being characterized by having the forward tip edge thereof in substantial alinement with the shank member and by having a tip member of self-hardening steel secured to and ex- 115
65

tending the full width across the forward side of the blade member.

7. A carbonizing retort having a longitudinally extending wall or retort shell with a longitudinally extending shaft therein 70 carrying paddles, each of which paddles comprises a shank member in the form of a rod that enters one of the shafts and that secures it in place on the shaft and a blade member secured to the shank member, each of which blade members has a resistance shoulder or pad, the construction being characterized by having the forward tip edge of the pad and the shank member in substantial alinement. 80

8. A carbonizing retort having a longitudinally extending wall or retort shell with a longitudinally extending rotary shaft therein that carries paddles, each of which paddles comprises a wrought metal shank member in 85 the form of a rod whereby the paddle is clamped in place on the shaft and a blade member cast upon the shank member, each blade member having a shoulder or pad that presses against the shaft when the paddle 90 is secured in place and also a blade portion arranged so that the operating face thereof makes a substantial slope with the axis of the shaft, the paddle construction being characterized by having the major portion 95 of the shoulder or pad extending rearwardly and by having the forward tip edge of the blade in alinement with the shank member. 100

9. A carbonizing furnace having a longitudinally extending inner wall or shell and 105 therein a longitudinally extending rotatable shaft, each of which paddles comprises a wrought metal shank member in the form of a bolt or rod for bolting the paddles in place on the shaft and a blade member each 110 of said blade members having a shoulder or pad for transmitting thrust from the paddle to the shaft, each blade member also having an operating face that makes a substantial slope with the axis of the shaft, the construction being characterized by having the forward tip edge of the blade in substantial alinement with the shank member and by having the shoulder or pad so that it extends rearwardly from the shank past a 115 plane which includes the axis of the shaft and which passes through the rear tip edge of the paddle. 120

10. In combination, a shaft, a paddle carried thereby comprising a shank member entering said shaft and serving to secure the paddle to the shaft, a blade secured to said shank and having a rearwardly extending resistance shoulder or pad in engagement with the shaft, the blade also having an operating face which makes a substantial slope with the axis of the shaft, the forward tip edge of the blade being in substantial alinement with the shank member, and the blade being provided with a self-hardening steel 125 130

member secured to the tip of said blade and extending the full width of the operating face of the blade.

5. 11. In combination, a shaft, a paddle carried thereby comprising a shank member entering said shaft and serving to secure the paddle to the shaft, a blade secured to said shank having a pad for transmitting thrust from the paddle to the shaft, the blade also
- 10 having an operating face making a substan-

tial slope with the axis of the shaft, the forward tip edge of the blade being in substantial alinement with the shank, and said pad extending rearwardly from the shank past a plane which includes the axis of the 15 shaft and passes through the rear tip edge of the paddle.

This specification signed this 19" day of November, 1919.

CHARLES HOWARD SMITH.
